UNITED STATES PATENT OFFICE.

REGINALD C. STEEPLE, OF SPOKANE, WASHINGTON, ASSIGNOR TO FRIELEY-VOSHARDT CO., OF CHICAGO, ILLINOIS, A CORPORATION OF ILLINOIS.

DESIGN FOR A FLUSH SWITCH PLATE.

•0,383.

Specification for Design.

Patented Feb. 7, 1922.

Application filed August 15, 1921. Serial No. 492,514. Term of patent 7 years.

To all whom it may concern:

Be it known that I, REGINALD C. STEEPLE, a citizen of the United States, residing at Spokane, in the county of Spokane and State of Washington, have invented a new, original, and ornamental Design for a Flush Switch Plate, of which the following is a specification, reference being had to the accompanying drawing, forming a part thereof.

Fig. 1 is a front view of a flush switch plate, showing my new design.

Fig. 2 is a side elevation of the same.

I claim:

The ornamental design for a flush switch plate, as shown.

REGINALD C. STEEPLE.
